UNITED STATES PATENT OFFICE

2,689,071

SETTING APPARATUS FOR TEXTILE FABRICS

Henry Richter, Kankakee, Ill., assignor to Paramount Textile Machinery Co., Kankakee, Ill., a corporation of Illinois

Application July 18, 1950, Serial No. 174,453

19 Claims. (Cl. 223—76)

1

This invention relates to improvements in setting apparatus for textile fabrics and its purpose is to provide improved means for setting and shaping stockings and other fabrics such as those formed by knitting linear condensation polyamide fibres which are known by the name of nylon. The present invention is an improvement in some respects over that described and claimed in my prior United States Letters Patent No. 2,451,978, granted October 19, 1948.

Shaped textile articles formed from nylon yarn, such as hosiery, are commonly subjected to a so-called presetting operation on forms of the required shapes in the presence of saturated steam for the purpose of reducing the resiliency of the knitted loops and removing the natural wrinkles of the loose fabric, thereby causing the articles to retain the shapes of the forms during subsequent washing and use. The setting treatment is carried on at a high temperature, preferably of from 240° Fahrenheit to 260° F. for a limited period and at a pressure above that of the atmosphere, thus necessitating the use of a closed chamber or retort in which the articles are contained during the operation.

In said Letters Patent there is disclosed a form of apparatus comprising a vertical retort having an upright door which is mounted on the inside of the retort and held in its closed position by internal steam pressure during the treatment of the hosiery. That door carries on its opposite sides two sets of forms for the hosiery or other fabric articles to be treated, so that one set of forms may be on the inside of the door within the retort for treatment at the same time that the other set of forms is on the outside of the retort accessible to the operator for preboarding and stripping operations. That form of apparatus has the advantage, among others, that a substantially continuous setting operation may be carried on by the use of the two sets of forms in succession without seriously interrupting the activities of the operator in stripping the set hosiery from one set of forms and placing untreated hosiery thereon.

The present invention provides an improvement upon the apparatus disclosed in said Letters Patent in that the door carrying two sets of boarding forms on its opposite sides is mounted on the outside of the retort and is rotatable about a vertical axis so that either set of forms may be presented to the interior of the retort to be subjected to the action of steam for setting purposes when the door is closed. With that arrangement, there is retained the advantage of the prior in-

2

vention in that one set of forms is accessible to the operator on the outside of the retort while hosiery is being treated upon the other set of forms within the retort and it has the advantage that, since the door is on the outside of the retort, the area of the retort may be relatively small, sufficient only to accommodate the forms which are within the retort, so that the volume of space to be filled with steam during the treatment is substantially reduced as compared with that required by the operation of the apparatus of the prior invention and the cost of operation is correspondingly lower.

A further improvement of the present invention lies in the fact that provision is made for subjecting the hosiery on the forms in the retort to the action of currents of hot air which are automatically injected as soon as the steam treatment is completed so that the hosiery on the forms within the retort is quickly dried and the door may be opened and reversed in its position after a relatively short interval to present a new batch of hosiery on the other set of forms within the retort for treatment, thereby greatly speeding up the operations of the apparatus and increasing the production as compared with the practice of the invention of said Letters Patent where the rotatable door is located within the retort and no provision is made for effecting a quick drying of the hosiery after the setting has taken place.

Still another object of the invention is to provide improved means for mounting the door on the outside of the retort for permitting the quick reversal of its position about a vertical axis so that either set of forms may be presented to the interior of the retort as desired. A further object is to provide improved means for latching the door in its closed position and to provide improved clamping mechanism for holding the door in its closed position against the pressure of the steam which is introduced into the retort for setting purposes.

A further object of the invention is to provide improved automatic controlling apparatus by which the sequence of operations carried out in the practice of the present invention is automatically controlled and effected in proper sequence and time duration. This control apparatus includes means for automatically operating the clamping means to hold the door in its closed position, means for introducing steam into the closed chamber, means for automatically operating louvers which control the opening and closing of the chamber, means for automatically introducing heated air into the chamber after the

steam treating operation and after the louvers have been opened, and means for automatically preventing the admission of steam to the retort when either the door or the louvers are open. Other objects relate to various features of construction and arrangement which will appear more fully hereinafter.

The nature of the invention will be understood from the following specification taken with the accompanying drawings in which one embodiment is illustrated. In the drawings,

Figure 1 shows a front elevation of setting apparatus embodying the features of the present invention;

Figure 2 shows a top plan view of the apparatus illustrated in Fig. 1;

Fig. 5 is a similar section taken on the same line 4—4 of Fig. 3 showing the door clamps in open position;

Fig. 6 shows a plan view of the operating mechanism located in the lower part of the housing shown in Figs. 1 and 3;

Fig. 7 is a horizontal section through the clutch mechanism shown in Fig. 6;

Fig. 8 shows an enlarged vertical section through the retort and the inlet and exhaust conduits showing the means for introducing hot air and exhausting air and steam from the retort;

Fig. 9 shows an enlarged vertical section taken on the line 9—9 of Fig. 6 showing the relative positions of the cams for controlling the clutch of the driving mechanism and the louvers of the drying system in the positions which they occupy when a cycle of operations of the apparatus has just been completed;

Fig. 9a shows the relative positions of the parts of the clutch when the parts of the control mechanism are in the relative positions shown in Fig. 9;

Fig. 10 is a sectional view similar to that of Fig. 9 illustrating the relative positions of the parts when the clutch members are engaged and the latch levers have been moved to a position to lock the clutch operating lever against movement;

Fig. 10a shows the relative positions of the parts of the clutch when the parts of the control mechanism are in the relative positions shown in Fig. 10;

Fig. 11 is a sectional view similar to that of Fig. 9 showing the relative positions of the parts of the control mechanism when one latch lever has been disengaged from the clutch operating lever;

Fig. 11a shows the clutch members partially disengaged to correspond to the position of the disengaged latch member illustrated in Fig. 11;

Fig. 12 is a sectional view similar to that of Fig. 9 showing the relative positions of the parts of the control mechanism after both latch levers have been disengaged from the clutch operating lever, thus permitting the clutch members to disengage completely, this being the condition which exists when steam is admitted to the retort and the louvers are closed;

Fig. 12a shows the relative positions of the parts of the clutch members when the parts of

the control mechanism occupy the relative positions illustrated in Fig. 12;

Fig. 13 is a sectional view similar to that of Fig. 9 showing the relative positions of the parts of the control mechanism upon further rotation of the cams after engagement of the clutch members, this being the condition which exists when the blower is about to come on to introduce hot air into the retort and when the clutch members are about to be disengaged;

Fig. 13a shows the relative positions of the clutch members when the parts of the control mechanism are in the relative positions shown in Fig. 13;

Fig. 14 is a sectional view similar to that of Fig. 9 showing the relative positions of the parts of the control mechanism after the louvers have been opened and the blower has been put into operation to introduce hot air into the retort with the clutch members disengaged;

Fig. 14a shows the relative positions of the parts of the clutch members when the parts of the control mechanism occupy the relative positions illustrated in Fig. 14;

Fig. 15 shows a side elevation of one of the door latches which serves to hold the door temporarily in closed position preliminary to the operation of the door clamps for holding the door;

Fig. 16 shows a horizontal section through parts of the door and the retort illustrating, in plan view, the door latches at opposite sides of the door;

Fig. 17 is a diagrammatic view of the circulatory system by which steam and hot air are introduced into the retort and exhausted therefrom; and

Figs. 18a and 18b show a diagram of the electric circuit by which the sequence of operations of the various parts of the apparatus is controlled.

As illustrated in the drawings, the invention is embodied in a form of apparatus comprising an upright channel-shaped metallic vessel 20 having side walls 20a, a back wall 20b, a bottom wall 20c, and a top wall 20d. These walls are preferably formed as a unitary structure and this retort is carried by a supporting base 21 having the form illustrated particularly in Figs. 1 and 3. As shown in Figs. 4 and 5, a baffle plate 22 is secured to and spaced upwardly from the bottom 20c of the retort and a steam inlet pipe 23 leads into the retort through the bottom wall beneath the baffle so that the steam spreads out beneath the baffle plate and then passes upwardly around the edges of this plate which are located inwardly from the outer walls and the door of the retort. An outlet pipe 24 leads outwardly from the middle point of the bottom wall 20c and this wall 20c may be sloped slightly toward the outlet 24 in order to carry away the condensate by gravity. The front opening of the retort 20 is closed by a door 25 which is adapted to be reversed in its position, as above referred to, and which is provided on opposite sides with rubber sealing strips 26 adapted to engage the front edges of the walls 20a, 20c and 20d of the retort in order to provide a fluid-tight closure. These sealing strips are tapered slightly from their inner surfaces toward their outer surfaces and are held in place by inner retaining members 27 and by outer sealing members 28 which have bevelled surfaces corresponding to those of the strips 26. The door 25 is made up of opposite steel plates 25a which are spaced apart by

I-beams 25b. These parts are welded together and the space between the plates 25a is filled with heat insulating material. The outer margins of the outer flanges of each I-beam 25b are connected by end plates 25c having their edges welded thereto. The retaining strips 27 are welded to the plates 25a and the strips 28 are secured by studs 29 to the plates 25a so that a rigid door structure is formed for providing a tight closure for the retort 20 and for supporting the hosiery forms 30.

One set of forms 30 is mounted on each face of the door 25, as shown particularly in Fig. 3. The forms 30 and their mounting are similar to those disclosed in said Letters Patent No. 2,451,978. Each form comprises a supporting bracket 31 and the several forms of each group are carried by a supporting frame 32 attached to the adjacent face of the door 25. Each bracket 31 comprises a U-shaped socket 31a adapted to rest upon a supporting rod 33 which extends transversely of the frame 32 and this frame also carries a transverse rod 34 extending parallel to the face of the drawings which is adapted to be engaged by the hook-shaped members 31b formed on the brackets 31 when the forms 30 are tilted away from the door for stripping or boarding purposes. The inner positions of the forms, which are illustrated in Fig. 3, are limited and determined by transverse rods 35 carried by the frame 32. In this manner, two sets of hosiery treating and drying forms are mounted on the opposite faces of the door 25 and either set of forms may be projected into the cavity of the retort when the other set is on the outside of the door to be worked upon by the operator. The horizontal area of the chamber of the retort may be only slightly greater than that necessary to accommodate a set of forms 30 and their supporting structure when the door is closed with these parts projecting into the retort, so that the volume of steam required for treating the hosiery on the forms is substantially limited as compared with former practice.

The door 25 is supported by a lower supporting arm 40 and an upper supporting arm 41, both of which are pivotally mounted upon a vertical shaft 42 having its lower end journalled in a bearing 43 and provided with a collar 44 which rests upon the bearing 43 and also supports the hub of the arm 40, thus providing support for the arm 40 and for the door 25 which is carried by the arm 40 through the agency of a trunnion 45 fixed to the lower transverse portion of the door frame and journalled in the outer hub portion 40a of the arm. A collar 46 is mounted between the hub portion 40a and a collar 47 secured upon the upper end of the trunnion 45, thus furnishing a thrust bearing for the door and its lower end. The upper end of the shaft 42 is journalled in an arm 48 secured to the upper wall of the retort by welding or the like and the extremity of the shaft 42 above the arm 48 is journalled in the outer hub portion 41a of the arm 41. The inner end of this arm has a hub portion 41b which has journalled thereon a trunnion 50 secured to the upper part of the door frame for supporting and guiding the door as it is moved to and from its closed position.

In order to guide the door and to permit it to be rotated about a vertical axis determined by the axis of the aligning trunnions 45 and 50, there is provided a guiding structure 55 which is illustrated particularly in Figs. 2 and 3 and which is mounted on the top of the retort 20 through

supporting legs 56. The legs 56 are attached to plates 57 which have secured thereto a transverse bar 58 and from this bar there extends in a forward direction a pair of parallel arms 59 to the forward ends of which there is secured an arcuate member 60 which forms a complete circle except for a gap 60a formed therein on the side thereof which is directed toward the upper part of the retort. A pair of spaced guides 61 and 62 are secured to the bar 58 and to the arms 59 and extend in a direction forwardly of the retort for guiding the door as it is moved to and from its closed position. The member 61 has its outer extremity flared outwardly in arcuate fashion as shown at 61a and the outer end of the other guide 62 is similarly flared outwardly as shown in 62a but this part is of greater extent than the portion 61a. These curved portions serve as tracks for rollers which engage them during the rotation of the door as hereinafter described.

The upper end of the spindle 50 engages the hub 66a of a bar 66 to which it is rigidly secured. The bar 66 extends at right angles to the vertical plane of the door 25 and has secured to the opposite ends thereof upwardly extending spindles 67 on which are rotatably mounted the guide rollers 68. At intermediate points on opposite sides of the axis of the spindle 50, the bar 66 is divided with upwardly extending spindles 69 on which are rotatably mounted two rollers 70 adapted to revolve within the arcuate guide number 60 when the door is rotated.

Upon referring to Fig. 2, it will be seen that either of the rollers 68 is adapted to travel between the guide members 61 and 62 when the door 25 is moved inwardly to its closed position. When the door is reversed, the other roller 68 serves this guiding function. When the door is moved outwardly so that both of the rollers 68 are out of engagement with the straight portions of the guide members 61 and 62, the door may be rotated about the vertical axis of the spindles 45 and 50 as indicated by dotted lines in Fig. 2. One of the rollers 68 is then adapted to travel upon the arcuate portions 61a and 62a of the guide members and at the same time the rollers 70 travel inside of the arcuate guide member 60. When the door has been reversed, it may then be moved inwardly again to its closed position with the other roller 68 travelling inwardly between the guide members 61 and 62. In this way, the door may be conveniently operated to position either set of forms 30 within the chamber of the retort 20.

The back wall 20b of the retort 20 is provided with an upper opening 20e which serves as an inlet for hot air which is admitted after the steam treatment of the articles on the forms in the retort, and this back wall 20b also has a lower opening 20f through which the steam, air and water condensate are exhausted during the drying operation. The opening 20e communicates with an inlet conduit 71 having flanges 71a which are secured by bolts 72 to a plate 73 having formed therein a port 73a through which the hot air is admitted to the inlet conduit. This port 73a is adapted to be closed by a gate valve 75 having a rubber sealing ring 75a around its margin to engage the surface of the plate 73 when the valve is closed. The valve is adapted to open by the action of gravity and it is closed by suitable operating connections comprising an arm 76 attached to the inner face of the valve member and pivotally connected to an operating link 77 which extends through the port 73a when the

valve is open. The other end of the link 77 is pivotally connected to a bell crank lever 78 which is pivotally supported at 79 on a bracket 80 carried by the plate 73. The other arm of the bell crank lever 78 is pivotally connected at 81 to an operating rod 82 which extends downwardly at the rear of the retort.

Hot air is directed to the port 73a through a tubular member 84a of rectangular cross section which forms a part of the casing of a heater unit 84. The part 84a has a flange secured to the plate 73 and it is adapted to convey hot air which is heated in the unit 84 by the action of steam coils, not illustrated, which are supplied with steam through the inlet pipe 85 and the outlet pipe 86. On the side thereof opposite the outlet conduit 84a, the heater unit 84 is provided with an opening bounded by an angle bar 88 which is attached to the mouth of a centrifugal fan or blower 89 adapted to be operated by an electric motor 90. When the motor is in operation air is forced through the heater unit 84 and the hot air is then discharged through the port 73a and the inlet conduit 71 to the interior of the retort 20, assuming that the gate valve 75 is then open.

The other opening 20f in the lower part of the back wall of the retort communicates with an outlet conduit 92 which has a flange 92a connected by bolts 93 with a metal plate 94. A gasket 95 is seated between these connected parts to provide a fluid-tight joint and the plate 94 is provided with a central opening 94a which serves as an outlet port for the hot air, steam and condensation which is discharged from the retort 20 when the blower 89 is in operation. The port 94a is adapted to be closed by a gate valve 96 which normally occupies an open position by gravity as shown in Fig. 8. The gate valve 96 is pivotally mounted at its lower edge on the plate 94 and is provided with an annular sealing ring 96a of rubber or the like which forms a fluid-tight connection with the surface of the plate 94 when the valve is closed. This valve is adapted to be moved to the closed position through a bracket 97 which is mounted on its inner side and pivotally connected with a link 98 adapted to extend through the opening 94a and having its other end pivotally connected at 99 to a bell crank lever 100 which is pivoted at 101 on a supporting bracket 102 carried by the plate 94. The other arm of the bell crank lever is pivotally connected at 103 to the previously mentioned rod 82 and it is also pivotally connected at this point to a link 104 which extends downwardly into the cavity of the supporting base 21 where it is pivotally connected to an operating lever 105. This lever is pivoted at 106 on a pedestal 107 and it carries at its free end a roller 105a adapted to be operated by a cam 108, the actuation of which will be hereinafter described. When the gate valve 96 is open, the air, steam and water of condensation within the retort is permitted to discharge through an exhaust conduit 110 which is connected to the plate 94 through an intermediate annular flanged member 111. This exhaust conduit may extend to any suitable point where its contents may be discharged.

Having described the retort and its reversible door, as well as the means by which steam and hot air are admitted to the retort, reference will now be made to the mechanism by which the door is operated and the means by which the admission of steam and hot air is controlled.

In order to secure the door 25 in its fully

closed position preliminary to the operation of the clamping mechanism by which the door may be more securely held against the steam pressure to be set up within the retort, the door is provided on opposite sides with latch mechanism designated generally by the numeral 115 and illustrated particularly in Figs. 3, 15 and 16. Each door latch comprises two relatively movable latch members one of which is adapted to secure the door in closed position in one position of the door, while the other is adapted to secure the door in closed position when it has been reversed by rotation about its vertical axis. One of these latch members 116 comprises two parallel members 116a which are connected at one end of the structure by a bolt 117 having a handle 118 mounted thereon. At their other ends, these members 116a are connected by a bolt 119. At an intermediate point, the members 116a are provided with hub portions 116b journaled upon a shaft 120 which has its ends secured in brackets 121 fixed to the end plates 25c of the door. One of the arms 116a of this latch member is provided with a plate 122 having a projecting tooth 122a provided with a bevelled edge 122b. This plate is adapted to interlock with a plate 123 attached to the side of the retort when the door is closed. As the door moves to its closed position, the bevelled edge 122b is adapted to ride over the edge of the locking plate 123 and then snap into position behind it in response to the action of a coil spring 124 which is attached at one end to a pin 125 carried by the member 116 and at its other end to a pin fixed on the door.

The other latching device of the unit 115 comprises two bars 127 and 128 which are located between the bars 116a and which are welded or otherwise secured to a tubular member 129 adapted to revolve upon the shaft 120. Both of the bars 127 and 128 extend in one direction from the tubular member 129 and having their free ends welded to a tubular handle 130 which is mounted around the intermediate portion 45 of the bolt 119 so that it is capable of tilting movement with respect to the frame 116 to the extent permitted by the difference between its internal diameter and the outside diameter of the bolt 119. The arm 127 of this latching device extends from the tubular hub portion 129 in a direction opposite to the handle portion 130 and it has secured thereto a latch plate 131 having an extending hook portion 131a provided with a bevelled edge 131b. When the door is closed with the handle 118 directed toward the retort, the bevelled edge 131b of the member 131 is adapted to ride over the edge of the locking plate 123a and thus latch the door in its closed position. The tooth 131 is adapted to be snapped into its locking position by the action of a coil spring 132 which is mounted in a cup-shaped member 133 carried by one arm 116a of the member 116 and arranged to engage a flange 134a extending laterally from a bracket 134 which is mounted on the short arm of the bar 127. A pin 135 is seated in the flange 134a and retains the spring 132 in position. By this arrangement one or the other of the latching devices of each unit 115 will engage the locking flanges 123 and 123a at one side of the door when the door is closed so that the door will be held in its fully closed position preliminary to the operation of the clamping mechanism which is now to be described.

As shown particularly in Figs. 1 and 3, the re-

retort 20, the clamping mechanism for the door, the means for controlling the admission and exhaust of hot air, and the operating mechanism are enclosed by an outer shell or housing 136 which has front panels 136a extending laterally from the edges of the door, side panels 136b, a rear panel 136c, and a top panel 136d, all of which are spaced from the retort 20 to the extent required to provide ample space within the shell or housing for the parts enclosed thereby. The door 25 is adapted to be secured in closed position against the action of the steam pressure within the retort by a series of clamping devices 140 each of which includes a clamping member 141 having an L-shaped arm 141a extending through an opening 136e in the front panel 136a of the housing. The extremity 141b of each clamping member is adapted to hook over the edge of the door 25 when the clamping member is in its operating position, as shown in Fig. 4, and each part 141b is provided with a contact screw 142 which may be adjusted to make proper contact at its inner end with the face of the outer door plate and which may be secured in adjusted position by a lock nut 143. These clamping devices 140 are spaced apart at intervals vertically along the retort so that the door is securely clamped at a plurality of points along both vertical edges, there being six such clamping devices along each edge of the door in the embodiment illustrated.

Each clamping device 140 also includes an actuating member 144 which is pivotally mounted at 143 on a supporting bracket 146 welded to a side wall 20a of the retort. The clamping member 141 of each clamping device is pivoted at 145 on the member 144 and a coil spring 147 is secured at one end to a pin 148 on the clamping member 141 and at the other end to a pin 149 on the actuating member 144. The clamping member 141 is also provided with an angular arm 141c which is engaged at its free end by a coil spring 150 seated in a tubular recess 151a formed in a boss 151 which is attached to the rearwardly extending arm 144a of the actuating member. The extent to which relative movement of the members 141 and 144 may take place in response to the action of the spring 150 is limited by the engagement of the inner part of the member 141 with the pin 149. The rearwardly extending arm 144a of each actuating member 144 is provided with a roller 153 which is adapted to ride upon the surface of a cam 154 mounted upon a vertical cam shaft 155. One of these shafts is located at each side of the retort and is journaled in bearings carried by the brackets 146 as shown particularly in Figs. 3 and 4. Upon rotation of the cam 154 in the direction indicated by the arrow 156, shown in Fig. 4, the actuating member 144 is operated to cause an angular movement of the member 144 and the member 141 about the pivot 143 so that the forward end of the clamping member is thereby tilted from the position shown in Fig. 5 to a position where the extremity 141b of the clamping member is positioned in front of the forward plate 25a of the door. Upon continued motion of the cam 154, the pivot 145 is carried around pivot 143 to cause the clamping member 141 to move bodily inward until the contact screw 142 on the free end of the clamping member engages the outer face of the door as shown in Fig. 4. The clamping operation is then completed with the roller 153 engaging the high point on the cam 154 and the parts remain in this clamped position during the

period that high pressure steam is contained within the retort 20. At the end of the treating operation, the rotation of the cams 154 is resumed and when the roller 153 engages the low point on the cam, as shown in Fig. 5, the clamping member 141 again moves to a position away from the door, as shown in Fig. 5, under the influence of a coil spring 157, connected to an arm 158 projecting rearwardly from the rearwardly extending arm 144a of the actuating member. Two of the springs 157 for clamping units at opposite sides of the retort are connected at the rear of the retort through a rod 159. During the operation of the clamping mechanism, the spring 150 of each clamping unit permits some relative movement of the parts 141 and 144, in case there is any interference with the free movement of the outer end of the clamping member, and the movement of the clamping member 141 toward the clamping position shown in Fig. 4 is limited by a stop screw 160 mounted in a bar 161 attached to the side of the retort and held in adjusted position by a set screw 162.

There is a vertical cam shaft 155 at each side of the retort as shown in Figs. 4 and 5 and each of these shafts has fixed thereon a plurality of the clamp operating cams 154 which are spaced apart as shown in Fig. 3. The two shafts 155 are adapted to be operated by a mechanism contained within the cavity of the supporting base or frame 21 and illustrated particularly in Figs. 6 to 14a, inclusive. Upon referring to Fig. 6, it will be seen that each shaft 155 is provided at its lower end with a relatively fixed bevelled gear 165, each of which meshes with another bevelled gear 166 mounted upon a transverse shaft 167 which is journaled in bearings 168 fixed on the frame structure 21. The shaft 167 has fixed thereon a gear 169 which meshes with another gear 170 fixed upon one shaft 171a of a power transmission unit 171. A transversely extending output shaft 171b of the unit 171 has fixed thereon a collar 172 and a clutch member 173 splined on the shaft 171b is separated from the member 172 by a coil spring 174 mounted around the shaft. Another coil spring 175 extends between a pin 176 on the collar 172 and another pin 177 on the clutch member 173 and tends to move the members 172 and 173 toward each other. The clutch member 173 is provided with a series of clutch teeth 173a which are adapted to interlock with other clutch teeth 178a formed on another clutch member 178 which is fixed upon a shaft 179a forming a part of a power transmission unit 179 which has its other shaft 179b connected through a coupling 180 with the shaft 181 of a driving motor 182. The motor 182 may be an electric motor which is in continuous operation while the retort is in use and when the clutch members 173 and 178 are engaged, the motor serves to drive the horizontal shaft 167 and also the two vertical cam shafts 155.

The previously described cam 108, shown in Fig. 8, which operates to close the valves or louvers 75 and 96, is mounted upon the horizontal shaft 167 and this shaft also operates to control the actuation of the cam shafts 155 through the clutch members 173 and 178. For this purpose, the clutch member 173 is provided with an annular groove 173b, shown in Figs. 6 and 7, which is engaged by the ball shaped ends of the bifurcated extremity 185a of a clutch lever 185 which is pivoted at 186 on a supporting bracket 187. This clutch lever is provided with an enlarged extremity 185b having a flat top and this end

of the lever also carries a pin 188 which is connected to a coil spring 189 having its other extremity attached to the casing of the motor 182 so that the spring operates normally to move the clutch member 173a to a position wherein it is disengaged from the clutch member 178. However, unless the clutch lever 185 is locked in the position shown in Fig. 6, wherein the clutch members are engaged, these clutch members tend normally to separate, independently of the spring 189, due to the wedging action of the bevelled edges of the clutch teeth 173a and 178a. After the teeth are disengaged by their own coaction, the spring 189 serves to effect a further movement of the clutch lever 185 to insure against any contact of the ends of the clutch teeth during the rotation of the clutch member 178.

The clutch member 173 is adapted to be moved into engagement with the clutch member 178 by the action of a solenoid 190 which has a magnetizable core 190a connected by a rod 191 with a bracket 192 fixed on the long arm of the clutch lever 185. The rod 191 is capable of being adjusted in length so that a precise degree of travel of the clutch member 173 may be obtained. When the solenoid 190 is energized as hereinafter described, the clutch lever 185 is moved toward the right as viewed in Fig. 6, and the clutch member 173 is thereby caused to engage the clutch member 178, whereupon the shaft 167 and the two cam shafts 155 are driven.

In order to hold the clutch lever 185 in a position wherein the clutch members are engaged, after the lever has been moved to that position by the energization of the solenoid 190, means are provided for engaging the end portion 185b of the clutch lever to lock it in that position. This means comprises two latch levers 195 and 196 which are shown particularly in Figs. 6 and 9 to 14, inclusive. The two latch levers are mounted on a common pivot 197 carried by a bracket 198 which is secured to a part of the supporting base 21. The lever 195 is provided at its inner end with a depending hook portion 195a which is adapted to interlock with the edge of the portion 185b of the clutch lever to hold the clutch members engaged and the other latch lever 196 is similarly provided with a depending hook portion 196a which is also adapted to drop down and engage the clutch lever for the same purpose. The latch levers are normally actuated to move the hook portions 195a and 196a downwardly into engagement with the clutch lever 185 by the action of coil springs 199 which are attached to the levers at the left of the pivot point 197, as viewed in Figs. 6 and 9 and which are connected at their upper ends to a stationary bracket 199a. The latch lever 195 is provided at its inner end with an upwardly extending tooth 195b and a similar tooth 196b is formed upon the inner end of the other latch lever 196. These teeth are adapted to be engaged by tripping pins 200, 201 and 202 which extend laterally from one face of a tripping disc 203 which is keyed upon the horizontal shaft 167. As the disc 203 is rotated in the direction of the arrow 204 shown in Fig. 9, the pins 200, 201 and 202 are caused to actuate the latch levers 195 and 196 to effect the release of the clutch lever 185 at proper intervals, at which times the clutch members 173 and 178 are disengaged and the rotation of the shafts 167 and 155 and of the cams mounted thereon is arrested. The tripping pins on the disc 203 are located to effect the release of the clutch lever 185 in the

proper sequence and timed relation to the various operations which are brought about by other parts of the apparatus, including the clamping of the doors and the operation of the louvers of the hot air system so that a complete cycle of operations is automatically effected as hereinafter described.

Some of the parts of the improved setting apparatus are illustrated somewhat diagrammatically in Fig. 17 which is intended primarily to show the connections for supplying and exhausting steam. As shown in this drawing, the compact arrangement of the apparatus of each unit permits a plurality of units to be arranged side by side and to be connected to the steam supply in parallel relationship so that a number of units of the apparatus may be operated conveniently at the same time. The supply of steam under pressure for all of the units is furnished by a supply pipe 210 which is arranged at the rear of the retorts. A branch pipe 211 leads from the main supply pipe through a manually operated valve 212 and to this pipe there is connected the previously mentioned supply pipe 85 by which steam is supplied to the air heater 84. Between the connection of the pipe 85 and the retort another manually operated valve 213 is connected in the supply pipe 211 and also an electrically operated steam inlet valve 215 which is automatically controlled to supply the steam to the retort 20 through the pipe 211 which leads to the inlet opening 23 previously referred to. The outlet port 24 in the bottom of the retort is connected with a steam exhaust pipe 216 which has connected therein the electrically operated steam outlet valve 217. A branch pipe 218 is connected to the pipe 216 between the retort and the valve 217 so that water condensation may flow off through this branch pipe which is adapted to be automatically opened when an excess of water is present through the actuation of a thermostatically operated valve 219 connected in this branch pipe and responsive to the temperature of the water therein.

A pipe 220 leading through the rear wall of the retort is connected to a pressure control switch 221 which is connected in the circuit hereinafter described and which is adapted to be actuated by the steam pressure in the retort for controlling the start of the timing period during which the steam is active in treating the articles on the forms. Another pipe 224 leads from the inlet conduit 71 to a pressure gauge 225 and two safety valves 226. These valves are adapted to relieve the pressure in the retort at the inlet of the steam supply when the steam pressure is excessive. At the rear of each air heater 84, there is provided a pipe 227 leading from the outlet steam pipe 86 through a trap 228 so that any condensate of steam collecting in the bottom of the water heater and in the exhaust pipe may flow out at this point.

The electric circuit for controlling the operation of the setting apparatus is shown somewhat diagrammatically in Figs. 18a and 18b. As there shown the electric current is furnished from a source of supply through line conductors 230 and 231 which have connected therein the fuses 232 and which lead to the double-pole main switch 233. When this switch is closed the circuit is completed to the main driving motor 182 which operates continuously during the desired series of cycles of operation of the apparatus.

Assuming that a number of articles of hosiery have been placed on the forms 30 on one side

of the door 25 and that the door has been moved to closed position where it is held by the latches 115, the action of closing the door will have operated to close the switches 234 and 235 which are safety switches connected in the circuit and positioned adjacent the door to prevent the steam inlet valve 215 and other devices from being operated when the door is open.

There is also connected in the circuit a manually operated push button switch 236 which is operated to initiate each cycle of operations of the apparatus. The closing of this switch energizes the holding relay 237 and also the clutch operating solenoid 190, thereby causing the clutch members 173 and 178 to engage and starting the rotation of the shafts 167 and 155. When the clutch members are engaged they are held engaged by the teeth 195a and 195b of the latch levers which drop down to the positions shown in Fig. 10. The rotation of the shafts 155 actuates the cams 154, thereby moving the clamping devices 140 from the position shown in Fig. 5 to the clamping position shown in Fig. 4 whereby the door 25 is held securely in closed position. At that point a cam 238 on the shaft 155 at the righthand side of the retort (see Fig. 3) closes a switch 240 (see Fig. 18a) which completes the circuit of the solenoid operated steam inlet valve 215, thereby allowing steam to enter the retort through the inlet port 23. Just before the steam is admitted, the cam 108 reaches the position shown in Fig. 10 and closes the louvers 75 and 96 (see Fig. 8) which are then held in closed position by the pressure of the steam during the steam treating period.

As soon as the louvers are closed and the steam is admitted, the clutch members 173, 178 are disengaged and the rotation of the shafts 155 and 167 is arrested. This is effected by the latch levers 195 and 196 which are actuated in succession by the pin 200 on the tripping disc 203 in the manner illustrated in Figs. 11 and 12. The pin 200 first engages the V-shaped tip 195b of the lever 195 and depresses it, thereby raising the tooth 195a of this lever out of engagement with the clutch lever 185 as shown in Fig. 11. The lever 185 then moves over into engagement with the tooth 196a of the other latch lever, which is farther away from the pivotal axis 197 of the levers than the tooth 195a, and the clutch teeth 173a and 178a partially disengage due to their wedging action on each other, as shown in Fig. 11a. As the pin 200 continues its travel, it depresses the tip 196b and disengages the tooth 196a from the lever 185, whereupon the clutch members move to the fully open position shown in Fig. 12a, in which relative positions they are held by the spring 189, and the end 185b of the clutch lever assumes a position beneath both of the teeth 195a and 195b, as shown in Fig. 12. This movement of the clutch lever 185 at this stage is permitted because the circuit of the clutch engaging solenoid 190 is then broken by a cam 241 fixed on the right-hand shaft 155 which opens a normally closed switch 242 at the proper time, thereby breaking the circuit of the solenoid switch 190.

When the temperature in the retort has risen to the desired amount, as indicated by the thermometer 243 shown in Fig. 17, following the admission of steam as described above, the thermostatically operated temperature controller 244, shown in Fig. 18a, acts through the relay 245 to complete the circuit of the treating timer 246 which then operates for a predetermined inter-

val, according to its setting, to determine the duration of the steam treatment of the fabric articles on the forms in the retort.

At the end of the predetermined interval, which 5 may be two or two and one-half minutes, for example, the timer 246 operates to energize the steam exhaust valve 217 through a normally closed relay 248 and at the same time the fan motor 90 is started in operation to drive hot air into the retort. When the steam pressure in the retort is thus relieved, the pressure switch 221 (see Fig. 17 and Fig. 18a) closes to complete the circuit of the fan timer 250 by which the duration of the hot air treatment is determined. At 10 the same time the clutch solenoid 190 is again energized through the relay 251 and the normally closed switch 252 controlled by a cam 253 on the right-hand shaft 155, thereby operating to engage the clutch members 173 and 178, so that 15 the shafts 167 and 155 are again rotated. The clutch members are then held engaged as before by the teeth 195a and 196a of the latch levers which drop behind the clutch lever as shown in Fig. 13. As the fan control cam 108 rotates, the 20 roller 105a (Figs. 8 and 13) drops into the depression 108a of the cam and permits the louvers or gate valves 75 and 96, which are now relieved of steam pressure, to drop by gravity to the open 25 positions shown in Fig. 8.

When the louvers have been opened and the fan motor started in operation, the latch levers 195 and 196 are tripped by the pin 201 of the tripping discs, thus permitting the clutch members 173 and 178 to disengage while the clutch 30 lever 185 again moves to a position beneath the latch lever teeth 195a and 196a, as shown in Fig. 14. The flow of hot air through the retort 20 for drying purposes then continues for a predetermined interval determined by the setting of the fan control timer 250. At the end of that 35 interval, the timer 250 operates to energize the relay 251 through a switch 255 which is controlled by a cam 256 fixed on the shaft 155 shown in Fig. 3, thus again energizing the clutch solenoid 190 to engage the clutch members 173, 178 and cause a new rotation of shafts 155 and 167 during which the clutch lever 185 is held in the operated position by the latch levers 195 and 196, the teeth of which drop behind the part 40 185a of the lever as previously described. As the shafts rotate the cams 154 cause the clamping devices 140 to move to the positions shown in Fig. 5 to release the door. Also, at the conclusion of the heating cycle, the timer 250 operates to energize the normally closed relay 258, thereby deenergizing the steam exhaust valve 217 and opening the circuit of the fan motor 90. When the door clamps are fully released from the doors, the latch levers 195 and 196 are 45 tripped by the pin 202 on the tripping disc and the clutch lever 185 again rides in beneath the teeth 195a and 196a of the levers as shown in Fig. 9 which illustrates the relative positions of these parts at the conclusion of a cycle. At this 50 stage all of the parts are fully restored to their initial positions and, after releasing the latches 115, reversing the door and moving the other set of forms into the retort, a new cycle of operations may be started by again actuating the switch 236.

The circuit shown in Figs. 18a and 18b also comprises a relay 260 which is connected to control the steam inlet valve 215 so that, if the temperature in the retort falls below the setting of the temperature controller 244 this relay op-

erates to cause the normally closed steam inlet valve to open and allow enough steam to enter the retort to raise the temperature therein to the desired extent. When the desired temperature is reached, the relay 260 is deenergized by the temperature controller and the steam inlet valve 215 is again closed. The relay 260 may be caused to operate on small fluctuations in temperature, for example, two degrees, Fahrenheit.

The primary purpose of employing two latch levers 195 and 196 having arms of different length, with their teeth spaced different distances from their pivot, is to permit one latch lever to be free to drop and lock the clutch lever 185 even before the rotation of the cams has started, thus insuring the continued engagement of the clutch after the solenoid 190 has been operated, even though the other latch lever may be held up by a pin of the tripping disc until after the rotation has started.

The circuit shown in Figs. 18a and 18b also includes branch circuits in which are connected two manually operated switches 262 and 263 which are used when it is desired to operate the apparatus for final boarding with the fan motor 90 running continuously. In that event, the main switch 233 is opened to cut off the automatic controls, the switch 262 is closed and the switch 263 is opened.

Although one form of the invention has been shown and described by way of illustration, it will be understood that it may be constructed in various other forms without departing from the scope of the appended claims.

I claim:

1. The combination in setting apparatus of the class described, of a stationary retort having a door opening, a door located entirely on the outside of said retort and mounted for rotation to present either face thereof inwardly, and forms mounted in upright position on both faces of said door for supporting textile articles.

2. The combination in setting apparatus of the class described, of a stationary retort having a door opening, a door located entirely on the outside of said retort for closing said opening, means for mounting said door to permit movement thereof bodily toward and away from said opening and to permit rotation thereof about a vertical axis, and forms mounted on both faces of said door for supporting textile articles.

3. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, and forms mounted on both faces of said door.

4. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, and means for introducing steam into said retort.

5. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof,

forms mounted on both faces of said door, means for introducing steam into said retort, means for permitting the exhaust of said steam from said retort, and means for then introducing hot air into said retort.

6. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, a plurality of clamps adapted to embrace the edges of said door to hold it in closed position with either face thereof presented inwardly, and means for simultaneously operating all of said clamps.

7. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, a plurality of clamps for holding said door in closed position with either side presented inwardly, means for introducing steam into said retort, and means for automatically operating said clamps and then operating said steam introducing means.

8. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, a plurality of clamps for holding said door in closed position with either side presented inwardly, means for introducing steam into said retort, means for exhausting steam from said retort, means for introducing hot air into said retort, and means for automatically causing the clamping of the door, the introduction of steam, the exhaust of steam, and the introduction of hot air to take place automatically in timed relation.

9. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, said retort having air inlet and outlet openings, louvers for closing said openings, means for introducing steam into said retort, and means for introducing hot air into said retort through one of said openings.

10. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, said retort having air inlet and outlet openings, louvers for closing said openings, means for introducing steam into said retort, means for permitting steam to exhaust from said retort, and means for introducing hot air through one of said open-

ings after the steam pressure in said retort has been relieved.

11. The combination in setting apparatus of the class described, of a stationary retort having a door opening, said retort having a door seat on the outside thereof, a reversible door on the outside of said retort adapted to present either face to said seat, means for mounting said door to permit rotary and bodily movement thereof, forms mounted on both faces of said door, said retort having inlet and outlet openings, means for introducing steam under pressure into said retort, inwardly opening louvers adapted to close said openings and to be held in closed position by the steam pressure in said retort, and means for relieving the steam pressure in said retort after a predetermined interval.

12. The combination in setting apparatus of the class described, of a stationary retort having a door opening, said retort having a door seat on the outside thereof, a reversible door on the outside of said retort adapted to present either face to said seat, forms mounted on both faces of said door, a series of clamps for engaging the edges of said door to hold the door in closed position, said retort having inlet and outlet openings, means for introducing hot air through one of said openings to said retort, means for introducing steam into said retort, and means including an electric circuit for automatically operating said clamps, said steam introducing means and said air introducing means.

13. The combination in setting apparatus of the class described, of a stationary retort having a door opening, said retort having a door seat on the outside thereof, a reversible door on the outside of said retort adapted to present either face to said seat, forms mounted on both faces of said door, a series of clamps for holding said door in closed position, means for introducing steam into said retort, means for exhausting said steam from said retort, said retort having inlet and outlet openings, louvers for closing said openings when steam is present in said retort, means for introducing hot air into said retort through one of said openings, and means including an electric circuit for effecting a sequential operation of said clamps, said steam introducing means, said steam exhausting means, said louvers and said air introducing means.

14. The combination in setting apparatus of the class described, of a retort having a door opening, a door located on the outside of said retort, a pair of supporting arms pivoted to the middle points of said door at its upper and lower edges and adapted to swing to permit said door to be moved bodily toward and away from said retort and to be rotated about a vertical axis, a series of forms mounted on each of the opposite faces of said door, and means mounted over said door for guiding the bodily movement of said door and for guiding said door during its rotation.

15. The combination in setting apparatus of the class described, of a retort having a door opening, a door located on the outside of said retort, a pair of supporting arms pivoted to the middle points of said door at its upper and lower edges and adapted to swing to permit said door to be moved bodily toward and away from said retort and to be rotated about a vertical axis, a series of forms mounted on each of the opposite faces of said door, a bar mounted on said door and extending transversely thereof, two pairs of rollers mounted on said bar, guide mem-

bers adapted to be engaged by the rollers of one pair during the bodily movement of the door, and guiding means adapted to be engaged by the other rollers during the rotation of the door.

16. The combination in setting apparatus of the class described, of a retort having a door opening, a door located on the outside of said retort, a pair of supporting arms pivoted to the middle points of said door at its upper and lower edges and adapted to swing to permit said door to be moved bodily toward and away from said retort and to be rotated about a vertical axis, a series of forms mounted on each of the opposite faces of said door, a bar mounted on said door and extending transversely thereof, two pairs of rollers mounted on said bar, guide members adapted to be engaged by the rollers of one pair during the bodily movement of the door, and guiding means adapted to be engaged by the other roller during the rotation of the door, said first named guiding means being adapted also to be engaged by the rollers of one pair during the rotation of said door.

17. The combination in setting apparatus of the class described, of a retort having a door opening, a door located on the outside of said retort and mounted for rotation to present either face of the door inwardly, forms mounted on the opposite faces of said door, locking plates carried by said retort at the sides of said door opening, and latching devices mounted on the opposite edges of said door and arranged to interlock with said plates with either face of the door presented inwardly, each of said locking devices comprising two relatively movable parts adapted to operate alternately for interlocking with one of said plates in accordance with the face of the door which is presented inwardly.

18. The combination in setting apparatus of the class described, of a retort having a door opening, a reversible door on the outside of said retort for closing said opening, forms mounted on both faces of said door to be projected into said retort, means for securing said door in closed position, means for introducing steam into said retort, and means for automatically preventing said introduction of steam when said securing means is not in operation.

19. The combination in setting apparatus of the class described, of a retort having a door opening, a reversible door on the outside of said retort for closing said opening, forms mounted on both faces of said door to be projected into said retort, means for securing said door in closed position, means for introducing steam into said retort, means for introducing hot air into said retort, and means for automatically preventing the introduction of either steam or hot air into said retort when said securing means is not in operation.
